US0D1101840S

(12) **United States Design Patent** (10) Patent No.: **US D1,101,840 S**
(45) Date of Patent: ** Nov. 11, 2025

(54) **EYEGLASSES WITH PARABOLOID LENSES**

(71) Applicant: **LUXOTTICA S.R.L.**, Agordo (IT)

(72) Inventors: **Nathalie Grosjean**, Milan (IT); **Daniel Sirena**, Rocca Pietore (IT); **Roberta Margherita Negretti**, Falcade (IT); **Maria Chiereghin**, Falcade (IT); **Cristiano Da Pian**, Alleghe (IT)

(73) Assignee: **LUXOTTICA S.R.L.**, Agordo (IT)

(**) Term: **15 Years**

(21) Appl. No.: **29/896,953**

(22) Filed: **Jul. 10, 2023**

(30) **Foreign Application Priority Data**

Jan. 10, 2023 (IT) 402023000000054

(51) **LOC (15) Cl.** **16-06**

(52) **U.S. Cl.**

USPC **D16/322**

(58) **Field of Classification Search**

USPC D16/300, 319, 320, 322, 325, 327, 329;

D29/102, 104–110

CPC G02C 5/02; G02C 1/026; G02C 1/06
